[57] **CLAIM**

The ornamental design for a container for perfumes and cosmetics products, as shown and described.

DESCRIPTION

FIG. 1 is a front elevation of the container for perfumes and cosmetic products of my design, the rear elevation being identical with FIG. 1;

FIG. 2 is a top plan view thereof; and,

FIG. 3 is a side elevation thereof, taken from either the left-hand side or right-hand side of FIG. 1.

The bottom of the container for perfumes and cosmetic products is flat and unornamented.
